DUAL PURPOSE PUMP

Eberhard E. Wetley, Chicago, Ill.

Application June 8, 1949, Serial No. 97,744

30 Claims. (Cl. 103—207)

This invention relates to a manually operable dual purpose pump for high pressure fluid delivery to a fluid operated mechanism and a pump that more specifically includes a second operative stage wherein the same pump functions to deliver a considerably larger fluid volume output to such fluid operated mechanism under low pressure demand conditions.

Numerous so called two-speed pumps have been developed to cope with this problem, but all are either too complicated and costly, or they have proven inefficient and impractical under actual operating conditions. The general trend has been to resort to dual cylinder structures having a double piston arrangement, but the difficulty in these designs has been to provide simple hand operated means therefor with sufficient mechanical advantage to be actually used with equal facility and ease to operate both stages of the dual cylinder or other two-speed pumps under normal high pressure fluid demand conditions. The high pressure stages of such pumps are so limited under hand manipulation that power driven equipment has been resorted to to actually serve the purpose, and such equipment is of the type that is pressure responsive to the demand and not the kind which would be suitable for manual work under the same conditions of use.

It is one of the main objects of this invention to provide a pump that is manually operable wherever needed to deliver fluid under high pressures to satisfactorily operate hydraulic or other fluid responsive equipment in their designed capacities and which pump is selectively automatically adapted to operate in a low pressure capacity to move relatively large volumes of fluid under low pressure conditions.

Fluid or hydraulic equipment mechanisms usually require lost motion operation before becoming effective to render service under high pressures. The result is that the hydraulic pump or pumps in any of these systems must operate at slow and time consuming intervals to move the members of each system into positions wherein their actual functions and purposes are ultimately rendered useful. By using a hand actuated pump designed for high pressure delivery in such systems the operator must spend much time and effort to move the parts acted upon by the pump through the fluid operable means until such parts become effective. And for all intents and purposes the high pressure design of such a pump is rather worthless as far as the low pressure manipulation thereof is concerned during the lost motion cycle period of the connected hydraulic or fluid equipment.

Another object of this invention, therefore, is to provide a manually operable pump that will actually serve in optimum capacity to move fluid under high pressure conditions and which will have the facility to throw off, so to speak, its normal high pressure function to effectively assume a rapid low pressure large fluid volume displacement cycle to quickly bring the coating parts of a fluid system into operative positions for subsequent and further action under a high pressure fluid delivery cycle.

It is a further object of the present design to provide a single cylinder pump having the dual purposes above related thus concurrently simplifying the structure for fabrication and at relatively low cost production values.

A further object of the pump is to perform the dual purpose functions thereof through reciprocating and rotative piston actuating mechanism, both actions being accomplished by the use of hand operable means which manipulate the piston within the confines of the single

2

cylinder structure. More specifically, the reciprocating piston action produces the large fluid volume displacement at low pressures while the rotative action of the piston produces the lower volume and high pressure fluid displacement.

Other objects and advantages relating to the design of the dual purpose pump of the present invention shall hereinafter appear in the following detailed description thereof having reference to the accompanying drawings forming a part of this specification.

In the drawings:

Fig. 1 is a front elevational view of the pump as the same would appear in one typical installation thereof to operate a fluid cylinder of a machinery hauling semi-trailer supporting foot;

Fig. 2 is a side elevational view of the pump structure as mounted upon the trailer with the latter in section substantially as viewed along the line 2—2 in Fig. 1;

Fig. 3 is a vertical axial cross sectional view through the pump proper and the connected valves with the piston retracted to the top of its stroke within the cylinder;

Fig. 4 is a similar cross sectional view of a fragmentary part of the pump illustrating the displacement feature of the piston when rotated to produce high pressure fluid displacement;

Figs. 5 and 6 are vertical cross sectional views taken transversely of the pump axis and as seen along the lines 5—5 and 6—6 respectively in Fig. 3 and looking in the direction of the arrows;

Fig. 7 is a fragmentary detail view partially in section to show the piston rod structure and its connection with the hand lever and piston of the pump;

Fig. 8 is a plan view of the piston actuating cam as viewed from the cylinder nesting end thereof, such cam being constructed as a stamping and providing a separable pump part;

Fig. 9 is a cross sectional view of the stamped metal cam as viewed along the line 9—9 in Fig. 8;

Fig. 10 shows a modified cylinder construction where-in the cam for the piston comprises an integral part of the cylinder head or cap;

Fig. 11 illustrates a solid cylinder with the cam cast or formed integrally into the end thereof to permit the use of the cylinder per se as a screw cap separable from its supporting base;

Fig. 12 is a fragmentary axial sectional view of a modified cylinder structure having a multipoint piston actuating cam which is designed to operate a coating cam piston under rotary actuation in either direction of rotation;

Fig. 13 is a cross sectional view of the cam end of the cylinder in Fig. 12 as seen along the line 13—13 in Fig. 12; and

Fig. 14 is another modified pump structure illustrating a contemplated variation in the manual operable lever and pump operating mechanism which is readily applicable to any of the other pump designs herein described and illustrated.

The pump shall be described as a hydraulic unit and obviously may be installed and operated for use in connection with any kind of a fluid system or fluid operated apparatus requiring a pump of this dual purpose character.

Figs. 1 and 2 depict a more specific installation of the pump 1 as applied for manual operable use in connection with a semi-trailer 2 having a hydraulically actuated supporting unit 3. The pump 1 comprising the device of the present invention has a cylinder 4 carried by a base 5 to secure one end of the cylinder in a conveniently usable position adjacent the apparatus served thereby, the cylinder 4 being closed at its other end by a head 6 as a screw cap adapted for assembly of the cylinder pump parts and to provide ready access to such parts and the interior of the cylinder when necessary.

Base 5 includes flat apertured flanges 7 for bolts 8 to secure the base firmly to a support such as the side channel 8a of the trailer 2. This base 5 as best shown in Figs. 1, 2 and 3 further contains the pump check valves with the inlet valve shown at 9 and the outlet valve shown at 10, both valves being of conventional types but preferably quick acting large volumetric capacity units.

to handle the maximum output of the pump without flow retardation and without placing added burden upon the operating mechanisms of the pump.

The fluid circuit is best shown in Figs. 2 and 3 with a fluid conduit 11 connecting a fluid reservoir 12 with the inlet valve 9 of the pump 1, while a fluid conduit 13 is connected with the outlet valve 10 and leads to one or more hydraulic cylinders 14 through suitable connecting conduits 15. Fluid from valve 9 enters the cylinder cavity 16 through a bore 17 and such fluid is discharged through a similar bore 18 to the outlet valve 10. In this manner the supporting foot 19 of the trailer 2 may be moved a distance 20 to the ground by the ram 21 of the foot cylinder 14. The hydraulic supporting unit 3 may be fixed to the trailer 2 or swingably mounted thereon as indicated by the connecting trunnions 22 to retract this gear when not in use. Suitable lock means is usually employed to hold the gear retracted or in vertical trailer raising or supporting position. Since this structure forms no part of this invention such lock means are not shown and further description is not deemed necessary, which also applies to the remainder of the fluid circuit operative to bypass the pump 1 and to provide means to lower the trailer by fluid outlet from cylinders 14 and back to the reservoir.

Fluid is moved through the cylinder 4 by means of a piston 23 secured to a piston rod 24 that rides in an opening 25 in the screw cap head 6 of the pump. The piston 23 may employ the usual cup seal 26 and one or more fluid rings 27 to prevent fluid bypass or leakage to the rear of the piston. The rear of the body of the piston 23 terminates in a pair of contiguous radially disposed cams 28 and 29 of predetermined pitch and helical in nature to form bilateral screw means for high pressure operation. Such cams 28 and 29 are best shown in Figs. 3, 4, and 6, and these cams coat with another pair of complementary contiguous radially disposed cams 30 and 31 formed upon a suitable stamping 32 terminating in a peripheral flange 33 that is sandwiched between the outer end 34 of the cylinder 4 and the inner face 35 of the screw head 6. The cam stamping 32 is thus fixed to the cylinder 4 and has an aperture 36 which permits the piston rod 24 to pass therethrough to actuate the piston 23.

It should also be noted that the high points of each of the pairs of coating cams are preferably beveled as shown at 37 on the piston cams and at 38 on the cylinder cams. These coating bevels 37-37 and 38-38 will cause a momentary pressure drop and fluid reversal in the cylinder immediately prior to the drop off steps 39 on the piston cams and 40 on the cylinder cams, the coating cams being well shown in Fig. 4 as positioned upon the receding bevels of the cams prior to the seating or nesting of the cams under a spring action mechanism to be described, the separation of the cams having been induced by relative rotation of the piston with respect to the fixed cylinder cam.

The spring action mechanism for holding the cam sets 28-29 and 30-31 in cooperative contact is best described with reference to Figs. 1, 2, 3 and 7. In Fig. 7 the piston rod 24 is shown with a squared end 41 seated in a square opening 42 in the piston 23 with the shoulders 43 on the round portion of the piston rod 23 abutting the face of the piston adjacent the square opening therein. The squared rod end 41 may be held socketed in piston 23 by suitable fastening means such as a nut 44 threaded upon the reduced stud 45 of the rod 24, and the other parts of the piston including the cup seal 26 are also secured to the piston by the same fastening means. The main purpose of this structure is to unify the piston and the rod whereby these elements may be considered integral for all intents and purposes to thus insure that the piston movements strictly follow the rod movements.

The other end of the piston rod 24 is squared at 46 and rides in a square opening 47 in a block 48 that has aligned studs 49 and 50 positioned to pass through slots 51 and 52 respectively formed in opposite legs 53 and 54 of a composite lever 55 shown in Figs. 1 and 2. Washers 56 and cotter pins 57 are carried by the studs 49 and 50 to reinforce this structure at this point although the opposite stud faces of block 48 against the adjacent leg faces will normally prevent cocking of the block and studs within the lever opening 58 formed by the offsets 59 and 60 in legs 53 and 54 of the lever 55.

A head 61 is secured to the end of the rod 24 and a

spring 62 is confined between said head and the block 48. Spring 62 normally urges the rod 24 to the left as viewed in Fig. 7, thereby holding the shoulders 63 of the round portion of rod 24 in abutting contact with the adjacent face of the block 48. Spring 62 may be of such selected strength to normally hold the parts in the relationship illustrated with the functional capacity to permit movement of rod 24 relative to the block 48 and lever 55 under one set of conditions of operation of the piston and pump.

Lever 55 is composite as noted by using symmetrical halves of formed metal bars comprising the legs 53 and 54. Legs 53 and 54 are secured together by rivets 64 above block 48 and by at least one shouldered stud rivet 65 below the block to dispose the lower ends of legs 53 and 54 in spaced relation to each other to receive an arm 66 of a rotary bracket 67 therebetween. Both lower ends of the legs 53 and 54 of the lever 55 are pivotally mounted at 63 to arm 66 of the bracket 67 thus providing the operational supporting means that positions lever 55 in operative relation to the pump. The opposite upper end of the lever 55 is angled at 69 to receive a rotational hand sleeve 70 thereon, and both the arm end 69 and sleeve 70 are positioned substantially horizontally or parallel to the pump axis when the pump parts are in the full line retracted positions indicated in Fig. 2.

Referring to the rotary bracket 67 as best shown in Figs. 2, 3 and 5, arm 66 has an offset 71 that terminates in a band bearing 72 which is rotatively mounted upon the cylindrical wall of the pump cylinder 4. This bracket band bearing 72 could be adjustably secured to the cylinder 4, but in the construction here used a sleeve or collar 73 is fastened to the cylinder 4 by one or more set screws 74 and in a location wherein the band bearing 72 abuts the shouldered screw head 6, the latter and the collar thus forming a peripheral channel within which the bracket 67 may be bodily rotated about the longitudinal axis of the pump 1 under which conditions the lever 55 is also bodily rotated about the aligned axes of the pump 1 and block 48.

The operation of the pump involves two separate actions which may be defined as reciprocatory and rotational, both, however, being solely confined to the cavity 16 of the single cylinder 4 and both utilizing the single piston 23 as the main fluid displacement means under the low and high pressure cycles of the device. During the period requiring fluid displacement under low pressure conditions for taking up the lost motion of the fluid actuated mechanical parts acted upon by the pump 1, as in the case where ram 21 in Fig. 2 must be advanced a distance 20 before becoming effective in its designed capacity, the pump is then actuated as a reciprocatory pump. Lever 55 is grasped by the hand below the sleeve 70 and beneath the angle portion 69 and is moved accurately back and forth about the pivotal means 68 as shown in Fig. 2 by the full line and broken line positions. With the use of a stud and slot structure for joining the block 48 and lever 55, a fixed pivotal means such as 68 is feasible. Also, spring 62 will act to return the rod 24 and piston 23 holding shoulders 63 of the rod 24 against the block 48, and on the power stroke the block 48 will automatically maintain its abutting relation to the rod shoulders 63 urging the piston the full length of cylinder 4 moving the entire fluid slug out of valve 10 to the hydraulic equipment. Cylinder 4 refills completely under the next retraction of the piston by drawing fluid from the reservoir 12 through valve 9.

After the foot 19 reaches the ground the fluid demand pressure increases sharply and hand reciprocation of lever 55 is automatically halted. This stage is easily detected by the operator since the resistance of the piston and connected parts against the lever 55 will prevent further forward manipulation thereof. When this occurs, the piston cams 28 and 29 will be in cooperative contact with the fixed cylinder cams 30 and 31. The operator may now shift his hand from the lever 55 to the hand sleeve 70 and swing the lever in a clockwise direction through the arc shown by the arrows in Fig. 1, bodily rotating piston 23 upon its axis within the cavity 16 of the cylinder 4 and about the long axis of the pump. With the dual cam arrangement, the piston 23 will be actuated forwardly in the cylinder twice each complete revolution of the lever 55 and each time by an amount equal to the maximum rise of the cams utilized. Spring 62 will retract the piston quickly at the completion of each cam

controlled forward stroke of the piston. Since the rotary action is rapid and the drop off of the cams rather instantaneous, the bevels 37-37 and 38-38 provide a split second reversal in fluid pressure within the pump to give the check valves 9 and 10 an opportunity to open and close respectively for quick fluid intake through valve 9 with the simultaneous entrapment thereof by valve 10. Each next successive power stroke by revolution will force a relatively large amount of fluid out of the same bore of the cylinder for approximately one half of a turn of lever 55, part of the half revolution being absorbed by the bevels which operative stage actually belongs to the intake stroke of the pump. The high pressure cam action stroke is well shown in Figs. 3 and 4.

In passing from low pressure stage to the high pressure stage the lever functions initially as a lever and secondarily as a crank. The separable cams provide means to build up considerable power on the piston longitudinally of the cylinder. The mechanical advantage obtainable by a selected given lever length acting substantially closely to or coincident with the axis of rotation of the cams that hug their axes of rotation is unlimited.

Suitable conventional venting means may be used to the rear of the piston 23 if necessary to prevent air lock or resistance. In the construction shown enough venting may be had through the opening 36 (see Figs. 8 and 9) through the stamping 32 here illustrated and through the bore 25 in the head 6. If further venting is needed, one or more vent holes 75 may be made in the stamping 32 to bypass air through one or more vents 76 drilled through the head 6.

The spring mechanism described and indicated in general at 77 in Fig. 2 will permit lever 55, as a crank, to be swung through its arc of operation without being subjected to the jiggling of the rod 24 and its piston 23. The experience of the operator will supplement the lost motion action at the connection of the piston rod to the lever. With a modified construction it is possible to lock the lever for use as a crank during the high pressure demand stage of the pump. Such a scheme is illustrated in Fig. 14 wherein arm 66 may have a segmental extension 78 with a suitable hole therein for alignment with a hole or holes 79 in the adjacent lever part or parts for the reception of a locking pin or the like. In addition, the band bearing 72 may have a second arm 80 positioned to ride between the lever legs that are here additionally offset upwardly at 81 to receive such arm therebetween. A pin 82 may be used to lock lever 55 to the arm 80 by insertion through suitably arranged openings in said arm and lever.

With either of the dual means shown in Fig. 14, it is possible to stabilize the position of the lever relative to the pump when the lever acts in the capacity of a crank during the high pressure cycle of the pump. The other parts will function in the same manner as in the first described device.

Attention is directed to the mounting of lever 55 in the structures illustrated in Figs. 2 and 14. The lever is made to straddle the arm 66 of the rotative bracket 67 to guide the lever in a plane radially disposed with respect to the pump axis to relieve the extending piston rod 24 of lateral stresses particularly when the lever is used as a crank. And whether arm 80 is used for locking purposes or not, the same does act in the capacity to further hold lever 55 in its operative plane with respect to the pump under either the reciprocatory or rotative stages of operation of the pump.

It should be noted that the reciprocation of the pump may be performed in any position of the 360 degrees about the pump axis. It may also be true that the piston and cylinder cams may not be lined up to nest fully when the pump is used as a reciprocation pump. But a rotational reversal of the lever in the opposite direction from the normal cam stroke rotation will align the cams so that manipulation of the handle or lever will give the piston its full stroke operation within the cylinder. Movement of the lever in the normal operative crank actuation direction can also be used to line up the cams to nest by listening to the snap of the cams into nested position. Continuing with the swinging of the handle or lever to reciprocate the piston will thereafter also yield a full stroke of fluid. Generally, whether the cams are fully nested or not is not objectionable particularly when considering the large capacity of the pump under the low pressure cycle.

In the forms described the crank or high pressure cam stage is only performable under unidirectional operation of the lever 55 due to the shape of the cams used. Figs. 12 and 13 show a pump of the same character using multipoint coating cams 83 and 84 connected with the cylinder 85 and piston 86 respectively. These cams are each designed with two high points 87-87 and two low points 88-88 with the contiguous joining cam surfaces rising and falling in each 90 degrees of the 360 degrees of cam surface. This eliminates the vertical drop off and obviously lengthens the time of the intake cycle. Furthermore, this provides symmetrical cams which allow axial rotation of the piston 86 in either direction by lever 55 to carry on the high pressure stage operation of the pump in the same manner as the first described pump.

Figs. 10 and 11 have been inserted to show the variations possible in providing the cylinder cam arrangement. In Fig. 3, the cylinder cam comprises the stamping 32 portrayed in Figs. 8 and 9 constituting a separable member securable into the cylinder by the joining screw head 6. Fig. 10 shows the cam 89 as cast or formed integrally with the head 90 to be screwed into place upon the cylinder 91. Fig. 11 shows a cam 92 cast or formed as an integral part of the cylinder 93 having a threaded end 94 for screw attachment at 95 with a threaded end 96 of a suitable base 97 which is provided with inlet and outlet ducts 98 and 99 as in the first described base 5. In the Fig. 12 structure, the head 100 is integral with cylinder 85 and cam 83 forms an integral part of the same to provide a design using the same principle of construction as indicated in the Fig. 11 version of the pump.

There are other changes and variations possible and contemplated in the dual purpose pump structures disclosed and described herein without departing from the fundamental concept of this invention. All such modifications and structural deviations shall, however, be governed by the breadth and scope of the language of the appended claims that are directed to the pump of this invention.

What I claim is:

1. In a pump, the combination of a cylinder, a piston therein, reciprocable means to bodily actuate said piston endwise within said cylinder, and a second means to independently actuate said piston within said cylinder comprising radially disposed cooperative means carried by opposed ends of said cylinder and said piston respectively, said cooperative means being rendered operatively responsive under relative rotation between said piston and said cylinder.

2. In a pump, the combination of a cylinder, a piston therein, shiftable mechanism carried by said cylinder and connected with said piston to bodily actuate the latter longitudinally in said cylinder, and a second mechanism to independently actuate said piston longitudinally in said cylinder comprising radially disposed coacting means carried by opposed ends of said cylinder and said piston respectively.

3. In a pump, the combination of a cylinder, a piston therein, reciprocable mechanism carried by said cylinder and connected with said piston to actuate the latter longitudinally in said cylinder, and a second mechanism to also actuate said piston longitudinally in said cylinder comprising radially disposed coating means carried by opposed ends of said cylinder and said piston respectively, said coating means being operably responsive under relative rotation between said piston and said cylinder, and one of the aforesaid mechanisms comprising operative means for inducing said relative rotation between said piston and said cylinder.

4. In a pump, the combination of a cylinder member and a piston member therein, said members being arranged for relatively longitudinal movement along their common axis and for relatively rotatable movement about said same common axis, operative means connected with one of said members to relatively actuate said members along said common axis, and further radially disposed operative means connected with opposed ends of both of said members to relatively actuate said members rotatively about their common axis and to also simultaneously actuate said members relatively to each other along the aforesaid common axis.

5. A pump comprising a cylinder, a piston disposed within said cylinder for reciprocatory and/or rotational

movement relative to said cylinder, and radially disposed coacting cooperative means carried by opposed ends of said cylinder and said piston to actuate said piston longitudinally of said cylinder during relative rotation between said cylinder and piston, and operative means connected with said piston to reciprocate the same within said cylinder independently of said cooperative means or to selectively induce relative rotation between said cylinder and said piston to simultaneously actuate the latter through said cooperative means.

6. A pump comprising a cylinder unit, a piston unit disposed within said cylinder unit for reciprocatory and/or rotational movement relative to said cylinder unit, and radially disposed coacting cooperative means carried by opposed ends of said cylinder unit and said piston unit to actuate said piston unit longitudinally of said cylinder unit during relative rotation between said units, and operative means connected with one of the aforesaid units to cause relative reciprocation between said units independently of said cooperative means or to selectively induce relative rotation between said units to thereby simultaneously actuate the units relatively and longitudinally with respect to each other through the aforesaid cooperative means.

7. A pump comprising a cylinder, a piston disposed within said cylinder for reciprocatory and/or rotational movement relative to said cylinder, radially disposed cooperative means carried by opposed ends of said cylinder and said piston and arranged to actuate said piston longitudinally of said cylinder during relative rotation between said piston and cylinder, and a piston rod guided by said cylinder and connected with said piston to reciprocate the latter independently of said cooperative means and adapted to selectively induce relative rotation between said piston and said cylinder to longitudinally actuate said piston in said cylinder through the instrumentality of said cooperative means.

8. A pump comprising a cylinder, a piston disposed within said cylinder for reciprocatory and/or rotational movement relative to said cylinder, cooperative means carried by said cylinder and by said piston and arranged to actuate said piston longitudinally of said cylinder during relative rotation between said piston and cylinder, a piston rod guided by said cylinder and connected with said piston to reciprocate the latter independently of said cooperative means and adapted to selectively induce relative rotation between said piston and said cylinder to longitudinally actuate said piston in said cylinder through the instrumentality of said cooperative means, a lever connected with said piston rod, and mounting means to support said lever for swingable motion to reciprocate said piston rod including a pivotal support for bodily rotation of said lever to rotate said piston rod and to actuate said piston by said cooperative means.

9. A pump comprising a cylinder, a piston therein, a piston rod carried by said cylinder and connected to actuate said piston, a lever connected with said rod, a bracket to pivotally support said lever to reciprocate said piston rod and the piston longitudinally to said cylinder, said bracket having pivotal connection with said cylinder to bodily rotate said lever and the connected rod and piston about the axis of said cylinder, and cooperative means interposed between said cylinder and said piston to longitudinally actuate the piston within said cylinder upon relative rotation between said piston and cylinder by said lever.

10. A pump comprising a cylinder, a piston therein, a piston rod carried by said cylinder and connected to actuate said piston, a lever connected with said rod, a bracket to pivotally support said lever to reciprocate said piston rod and the piston longitudinally to said cylinder, said bracket having pivotal connection with said cylinder to bodily rotate said lever and the connected rod and piston about the axis of said cylinder, and cooperative means interposed between said cylinder and said piston to longitudinally actuate the piston within said cylinder upon relative rotation between said piston and cylinder by said lever, said cooperative means comprising coacting cams carried by said piston and by said cylinder respectively.

11. A pump comprising a cylinder, a piston therein, a piston rod carried by said cylinder and connected to actuate said piston, a lever connected with said rod, a bracket to pivotally support said lever to reciprocate said piston rod and the piston longitudinally to said cylinder,

said bracket having pivotal connection with said cylinder to bodily rotate said lever and the connected rod and piston about the axis of said cylinder, and cooperative means interposed between said cylinder and said piston to longitudinally actuate the piston within said cylinder upon relative rotation between said piston and cylinder by said lever, said cooperative means comprising coacting cams carried by said piston and by said cylinder respectively, said cams each having their effective coacting cam surface contours disposed in operative planes positioned generally radially to the axis of said cylinder, and said cams being rendered ineffective during the reciprocation of said piston while being rendered fully effective during the relative rotation of said piston with respect to said cylinder.

12. In a pump, in combination with a cylinder and a piston, a lever connected to reciprocate said piston, a bracket carried by said cylinder for bodily rotation about the axis of the latter, pivotal means connecting said lever with said bracket to permit oscillation of said lever in a direction to reciprocate said piston, and cooperative cam means connected with a fixed part of said cylinder and with said movable piston respectively and arranged to actuate said piston longitudinally of said cylinder during relative rotation between said piston and cylinder by said lever and the rotatably mounted bracket.

13. In a pump, in combination with a cylinder and a piston, a lever connected to reciprocate said piston, a bracket carried by said cylinder for bodily rotation about the axis of the latter, pivotal means connecting said lever with said bracket to permit oscillation of said lever in a direction to reciprocate said piston, and cooperative cam means connected with a fixed part of said cylinder and with said movable piston respectively and arranged to actuate said piston longitudinally of said cylinder during relative rotation between said piston and cylinder by said lever and the rotatably mounted bracket, said cooperative cam means being located at one end of said cylinder and upon an adjacent face of said piston respectively for operative coaction when said piston is brought to said one end of said cylinder by said lever, and resilient means connected with said piston to urge said cam means into operative contact during bodily rotation of said lever to thereby actuate said piston through said cooperative cam means.

14. In a pump, a cylinder, a piston therein, a piston rod connected with said piston and projecting from one end of said cylinder, a bracket pivotally mounted upon said cylinder to revolve about the axis of the latter, a lever pivotally carried by said bracket to oscillate in any plane coincident with the axis of said cylinder, operative means for connecting said lever with said piston rod to permit reciprocation of said piston within said cylinder by said lever, and coacting cams carried at one end of said cylinder and on an adjacent side of said piston and arranged to urge said piston longitudinally of said cylinder by relative rotation of the piston with respect to said cylinder, said lever comprising means to move said cams into operative contact and to actuate the same by rotating said piston with respect to said cylinder.

15. In a pump, a cylinder, a piston therein, a piston rod connected with said piston and projecting from one end of said cylinder, a bracket pivotally mounted upon said cylinder to revolve about the axis of the latter, a lever pivotally carried by said bracket to oscillate in any plane coincident with the axis of said cylinder, operative means for connecting said lever with said piston rod to permit reciprocation of said piston within said cylinder by said lever, and coacting cams carried at one end of said cylinder and on an adjacent side of said piston and arranged to urge said piston longitudinally of said cylinder by relative rotation of the piston with respect to said cylinder, said lever comprising means to move said cams into operative contact and to actuate the same by rotating said piston with respect to said cylinder, and said operative means including resilient mechanism to provide a lost motion connection between said lever and piston rod to effectively join the latter under direct reciprocation of said piston but to permit relative movement between said lever and the piston rod during rotation of the lever when said piston is actuated by said coacting cams.

16. In a pump, a cylinder, a piston therein, a rod for said piston projecting from said cylinder, a bracket

carried upon said cylinder to bodily swing about the axis of the latter, a lever pivotally carried by said bracket for operation in the axial direction of said cylinder, and operative means to connect the rod with said lever in line with said cylinder to permit reciprocation of the piston by said lever, said cylinder and the piston having cooperative cam means at the rod end of the pump arranged to actuate said piston longitudinally in one direction within said cylinder upon relative rotation between the piston and cylinder by said lever and the rod, and spring means connected with said operable means to normally urge said rod in the other direction to retract said piston after cam actuation in the aforesaid one direction.

17. In a pump, a cylinder, a piston therein, a rod for said piston projecting from said cylinder, a bracket carried upon said cylinder to bodily swing about the axis of the latter, a lever pivotally carried by said bracket for operation in the axial direction of said cylinder, and operative means to connect the rod with said lever in line with said cylinder to permit reciprocation of the piston by said lever, said cylinder and the piston having cooperative cam means at the rod end of the pump arranged to actuate said piston longitudinally in one direction within said cylinder upon relative rotation between the piston and cylinder by said lever and the rod, and spring means connected with said operable means to normally urge said rod in the other direction to retract said piston after cam actuation in the aforesaid one direction, said lever having a shank portion at its free end to provide a hand grasp to manually oscillate the lever for reciprocation of the piston, and said lever shank portion having a bent terminal end disposed generally parallel to the cylinder axis when the lever is retracted for cam actuation of the piston, said bent end forming a hand grip to conveniently rotate said lever and bracket about the axis of said cylinder.

18. In a pump, a crank constituting a bent lever, a bracket to pivotally support said lever, a cylinder, said bracket being mounted for rotation on said cylinder and about the axis thereof, a piston, a rod connected with said piston and with said lever on the axial line of said cylinder, said lever comprising means to reciprocate said piston between certain limits, operative cam means within said cylinder to actuate said piston between certain other limits upon rotation of said lever in a predetermined plane of operation, and cooperative locking means carried by said bracket and said lever respectively to position said bent lever in said operative plane for actuation of said operative cam means to move said piston by the rotation of said bent lever.

19. A pump comprising a cylinder, a piston, a first means to reciprocate the piston, a second means to actuate said same piston within said cylinder comprising cooperative cams carried by the cylinder and the piston respectively and operable by relative rotation of the piston with respect to the cylinder, said cams each comprising high and low points disposed in the axial direction of the cylinder and adapted for alternate opposite engagement when rotated to urge the piston axially of said cylinder in one direction, and resilient means connected with said piston to urge said cams into nesting contact in the opposite direction within said cylinder.

20. In a pump, the combination of a cylinder having fluid inlet and outlet ports at one end thereof, a piston, actuating means to reciprocate said piston within said cylinder including coacting cams carried at the other end of said cylinder and by the piston respectively, said actuating means comprising a reciprocable member connected to move the piston through the full length of said cylinder, said member being rotatably mounted to induce relative movement between said piston and said cylinder whereby said cams are rendered operative to move said piston during the rotation of said member when the latter is held in retracted position at the cam end at said other end of the cylinder.

21. A pump comprising a cylinder, a piston, a first means to reciprocate the piston, a second means to actuate said same piston within said cylinder comprising cooperative cams carried by the cylinder and the piston respectively and operable by relative rotation of the piston with respect to the cylinder, said cams each comprising a plurality of inclined planes terminating in abrupt drop-offs disposed in the axial direction of the cylinder whereby said cooperative cams function to urge

said piston axially of said cylinder in one direction, and resilient means connected with said piston to urge said cams together in the other direction within said cylinder.

22. A pump comprising a cylinder, a piston, a first means to reciprocate the piston, a second means to actuate said same piston within said cylinder comprising cooperative cams carried by the cylinder and the piston respectively and operable by relative rotation of the piston with respect to the cylinder, said cams each comprising a plurality of inclined planes terminating in abrupt drop-offs disposed in the axial direction of the cylinder whereby said cooperative cams function to urge said piston axially of said cylinder in one direction, and resilient means connected with said piston to urge said cams together in the other direction within said cylinder, and said cams each having limited portions of said inclined planes beveled adjacent to said drop-offs to partially reverse the direction of said piston in said cylinder under the action of said resilient means immediately prior to the nesting of said cams at the drop-off positions of the cams.

23. A fluid pump comprising a cylinder, a piston, a rod to reciprocate said piston the full length of said cylinder, an oscillatory member connected to reciprocate said rod, mounting means to support said oscillatory member in a given relation with respect to said cylinder and for bodily rotation about the axis of said cylinder, and coacting cams carried by said cylinder and by said piston respectively to actuate said piston through a portion of the cylinder length upon rotation of said piston and said rod through the instrumentality of said oscillatory member.

24. A dual pressure fluid pump comprising a fluid cylinder having a given length, a piston therein to negotiate the length of said cylinder, an actuating rod secured to said piston to bodily reciprocate the same, and coacting cam means interposed between said cylinder and said piston to urge said piston lengthwise through a portion of said cylinder, said cam means comprising a first cam connected with said cylinder with the cam surface portion thereof arranged to face said piston and a second cam connected with the adjacent surface of said piston and having the cam surface portion thereof arranged to face said first cam, said piston being bodily actuated through the length of said cylinder by endwise movement of said rod, and said piston being partially actuated through said cylinder by said cam means upon rotation of the piston by said rod.

25. A dual purpose pump comprising a cylinder, a piston member therein, an unrestrained rotatable and freely endwise movable actuating member carried by said cylinder and connected with said piston member to motivate the latter, and coacting bodily separable cam means carried on one of said members and secured in fixed relation on said cylinder respectively, said piston member being endwise operable in said cylinder by rectilinear motion of said actuating member and also endwise operable in said cylinder by said cam means upon rotational motion of said actuating member when said separable cam means are adjacently positioned.

26. In a fluid pump, a cylinder, a reciprocable mechanism comprising a piston in said cylinder and a rod for said piston slidably carried by said cylinder and being adapted to bodily reciprocate said piston throughout the length of said cylinder, and coacting cams carried at one end of said cylinder and upon an adjacent face of said piston respectively, said cams being rendered operative when said piston is positioned adjacent said cam end of said cylinder, and said rod comprising means to actuate said cams to move said piston along a portion of the length of said cylinder upon rotation of said piston by said rod.

27. In a fluid pump, a cylinder, a reciprocable mechanism comprising a piston in said cylinder and a rod for said piston slidably carried by said cylinder and being adapted to bodily reciprocate said piston throughout the length of said cylinder, and coacting cams carried at one end of said cylinder and upon an adjacent face of said piston respectively, said cams being rendered operative when said piston is positioned adjacent said cam end of said cylinder, said rod comprising means to actuate said cams to move said piston along a portion of the length of said cylinder upon rotation of said piston by said rod, and automatic biasing means connected with said reciprocable mechanism to normally urge that

11

mechanism in a direction with respect to said cylinder so as to bring said cams into cooperative relation.

28. A dual pressure fluid pump comprising a casing, a plunger in said casing, a push rod for said plunger slidably carried in one wall of said casing and being adapted to bodily reciprocate said plunger throughout the length of said casing under certain fluid pressure conditions, and cam members associated with one end of said casing and with said plunger respectively, said casing cam member being arranged to surround said push rod and to face inwardly of said casing, and said plunger cam member being connected with said rod and arranged adjacent one face of said plunger surrounding said push rod and facing said casing cam member, said cam members being rendered coactively operative only when said plunger is positioned at the cam member end of the casing, and said push rod comprising means to actuate said plunger over a portion of the length of said casing during rotation of said plunger cam relative to said casing cam by rotation of said push rod with respect to said casing and under certain other fluid pressure conditions.

29. In a fluid pump, a cylinder, a piston carried in said cylinder and axially movable therein, a piston rod slidably mounted on said cylinder and connected with said piston for bodily reciprocating said piston within said cylinder, a first cam constructed and arranged for fixed connection with said cylinder at a given position along the axis thereof, a second coating cam constructed and arranged for connection with said piston and directly movable with said piston toward and away

12

from said first cam, said rod comprising means to actuate said cams into operative contact within said cylinder, and said cams when in contact comprising rotatively operable means functioning to actuate said piston axially within said cylinder when said piston is rotated with respect to said cylinder by means of said piston rod.

30. A fluid pump comprising a cylinder, a piston in said cylinder, a relatively separable radially disposed cam members connected with said cylinder and piston respectively, reciprocable means connected with said piston to actuate said piston within said cylinder and to cause alternate separation and meeting of said cam members, said reciprocable means being rotatable relative to said cylinder to operate said cam member when said members are disposed in meeting contact by said reciprocable means whereby said piston is selectively cam actuated within said cylinder.
